UNITED STATES PATENT OFFICE

2,589,177

COMBUSTIBLE CORE FOR FORMING DUCTS
IN CONCRETE STRUCTURES

Warner F. Wilhelm and Warren F. Wilhelm, Chicago, Ill.; said Warner F. Wilhelm assignor to Cora M. Wilhelm, Chicago, Ill.

Application March 27, 1948, Serial No. 17,456

4 Claims. (Cl. 25—128)

1

In our co-pending application, Serial Number 555,415, filed September 23, 1944, now Patent No. 2,438,528 of which the present application is in part a continuation, we have described and claimed methods and means for the draining of excess water from plastic cement, concrete and the like. We have found that by suitable modification of the invention described and claimed in the aforementioned parent application, it is possible to produce shaped passageways in cement, concrete and similar structures, accompanied or not, as desired, by the drainage of excess water from said structures while in plastic condition. These passageways are adaptable to many uses. For example, they may serve as conduits for electric wire or cable, as pipes for the transportation of liquids or gases, as points of attachment for various structures exterior to the cement or concrete, et cetera.

It is an object of this invention to provide means for the formation of shaped passageways in cement, concrete and similar structures.

A further object of this invention is to provide means for facilitating the drainage of excess water from plastic cement, concrete or similar structures and the formation of shaped passageways in said structures.

Additional objects of this invention will become apparent as the description thereof proceeds.

For the better understanding of this invention, reference may be had to the accompanying sheets of drawings, wherein:

Figures 1 to 5 are cross sectional views of several modifications of one form of device suitable for accomplishing the objects of this invention;

Figures 6 and 7 are cross sectional views of modifications of another form of device suitable for accomplishing the objects of this invention;

Figure 8 is a cross sectional view of a third form of device suitable for accomplishing the objects of this invention; and

Figures 9 to 16 are isometric views of several suitable methods of employing the devices of Figures 1 to 8 for accomplishing the objects of this invention.

Turning now to a more detailed description of Figure 1, reference character 1 designates a general cross sectional view of a device suitable for accomplishing the objects of this invention, consisting of a relatively or completely water impervious layer or sheath 2 and a core 3 capable of self-sustained combustion in the absence of air. One mode of application of the device of Figure 1 for accomplishing the objects of this invention is shown generally in Figures 9 and 10.

2

In Figure 9, the end closure of a cement or concrete form is designated by 10, while the side closures of said form are designated 11. End closure 10 is provided with an opening 12 through which a free end of the device of Figure 1 extends. The form is filled with plastic cement or concrete to the approximate level indicated by 13 and the device of Figure 1 is laid along the surface thereof following which additional plastic cement or concrete is added to the form to the level desired for the particular structure being made. Figure 10 is exemplary of a portion of a completed cement or concrete structure with the form removed and with the device of Figure 1 extending therethrough. The water impervious sheath 2 (Figure 1) obviously protects the core 3 (Figure 1) from deterioration. On ignition of the core 3 (Figure 1) combustion proceeds throughout its length and a shaped passageway is formed in the cement or concrete, thereby accomplishing the objects of this invention.

It is not necessary that the form be partially filled with cement or concrete, the device of Figure 1 laid on the surface thereof, and the remaining cement or concrete added as above described. If desired, the device of Figure 1 may be positioned in an empty form following which the whole charge of cement or concrete is added. When proceeding in this manner, it is necessary that care be exercised to prevent dislodgment or breaking of the device of Figure 1 as the heavy cement or concrete is poured into the form.

Also, it is not necessary that a material of the physical characteristics of freshly prepared cement or concrete be employed. Solids of particulate form, as well as certain liquids, are equally adaptable. For example, a liquid monomer that reacts to form a solid polymer through the action of heat, catalysts or the mere passage of time is suitable. Likewise, liquids that change to solids on reduction of temperature are applicable, for example, water. Solid polymers in particulate form which are convertible to consolidated solids by the application of heat and/or pressure (injection or compression molding) can be used. Also, this invention may be applied to particulate solids such as coal, sand, soil and the like. Sand, for example, may be poured around positioned devices of Figure 1 if freezing weather is expected. When required for use, the frozen mass of sand may be thawed by ignition of the cores.

While the broad principles of the instant invention have been generally set forth above, many specific modifications may be employed

without departing from the spirit or scope thereof.

The relatively or completely water impervious sheath 2 may itself be combustible or non-combustible, as desired. Preferably, this sheath is flexible to facilitate the formation of passageways with bends, curves, et cetera, as may be desired or necessary. A sheath of cellulose acetate or nitrate or a mixture of the two may be used if a combustible sheath is desired. Vinyl chloride or vinylidene chloride polymers, natural or synthetic rubber also are suitable for use as sheathing materials. However, sheaths exhibiting a satisfactory resistance to penetration by water can be prepared simply by the application of suitable glazes, asphalt, tar or the like to woven materials. For example, by methods well known in the art, the outer surface of ordinary black powder fuse can be rendered relatively water impervious by glazing and/or impregnation with asphalt or tar. A common specification for such relatively impervious fuse requires that it withstand water immersion for sixteen hours at a depth of thirty inches without deterioration. Obviously, this degree of water resistance is sufficient for the purposes of the present invention. Sufficient water resistance may also be conferred on woven sheaths by impregnation with silicone resins by methods now well known to those skilled in the art.

The core 3 may take a wide variety of forms without departing from the spirit or scope of the present invention. Once ignited, it is desired that combustion of the core proceed at a reasonably fast rate but, at the same time, it is necessary that this rate at no time approach too great proportions. Ordinary black powder fuse satisfies these requirements under most circumstances, especially when relatively short lengths are employed. This fuse is usually made with a burning rate of 30 to 40 seconds per foot and the combustion of the black powder core, which is accompanied by combustion of a considerable proportion of the surrounding fibrous members, results in the formation of shaped passageways in the cement, concrete or similar structure, thereby accomplishing the objects of this invention. Another suitable core material consists of combustible particles such as alpha cellulose particles, part or all of which are impregnated with an oxygen supplying agent such as potassium, sodium or ammonium nitrate, chlorate or perchlorate.

Many variations in the structure of the core are possible without departing from the spirit or scope of the present invention. Some of these modifications are shown in Figures 2, 3 and 4.

In Figure 2, the device 1, consisting of a relatively or completely impervious sheath 2 surrounding a core 3 is shown as before, core 3 being made up of a plurality of elongated fibers 4 capable of self-sustained combustion. These fibers may take the form of elongated strings made from cotton or similar fibrous materials. These are impregnated with a suitable chemical for supplying oxygen such as potassium, sodium or ammonium nitrates, chlorates, perchlorates or the like. The rate of combustion of the core 3 of the type shown in Figure 2 may be controlled by impregnating only a certain portion of the fibers with the oxygen supplying compound. This is shown in Figure 3, in which a portion of the fibers are impregnated with the oxygen supplying compound (these being designated 4) while the remainder of the fibers (designated

5) are not impregnated. Of course, sufficient impregnated fibers are present to insure self-sustained combustion of the whole. Yet another modification is shown in Figure 4, in which the core 3 carries along a portion or all of the longitudinal dimension thereof a train 6 exhibiting a considerably more rapid combustion rate than that of the core proper. On ignition, the train 6 rapidly transmits combustion along the whole length of the train, and this ignites the contiguous portion of the slow burning core 3 in a relatively short period of time. After ignition, the core smolders until combustion is complete and the desired passageway has been formed.

While it is comparatively simple to fix the rate of combustion of core 3 at any desired value on the basis of experimental determinations made on short lengths of 1 in air or embedded in concrete, cement or similar structures, it has been found that the results of such experimental determinations of combustion rate are not necessarily applicable to long lengths of 1 embedded in concrete, cement or similar structures. Frequently, the rate of combustion of core 3 in long runs of device 1 embedded in cement, concrete or similar structures is considerably higher than would be predicted on the basis of experiments made with short lengths of 1. We have arrived at a simple explanation of this phenomenon which we believe to be accurate, but we do not wish to be bound by any theory proposed. It is well known that the rate of combustion of black powder, for example, varies directly with pressure. In mining operations, for example, it has long been recognized that the burning rate of a fuse that has been thoroughly and tightly stemmed in a shot hole is appreciably higher than that of a fuse that is not stemmed or is only loosely stemmed. With respect to the present invention, it is evident that during the combustion of core 3 of a long run of 1 embedded in cement, concrete or a similar structure, a point is reached where the products of combustion are unable to escape from the combustion zone as rapidly as they are produced due to increasing pressure drop along the passageway being formed. As a result, the pressure at the point of combustion rises above normal which results in an increase in combustion rate. Obviously, this phenomenon is auto-accelerating and in extremely long runs the combustion rate may reach a very high value.

We have been successful in avoiding this auto-accelerating combustion phenomenon in long lengths of 1, by forming said long lengths with cores 3 of a progressively changing rate of combustion. For example, with the device of Figure 1, having a core 3 containing material of particulate form capable of self-sustained combustion, for example, black powder or cellulose particles impregnated with an oxygen supplying material, the composition of the core is varied along its length, being relatively rich in material capable of self-sustained combustion at one extremity and containing considerable diluent at the other. As is well known, the rate of combustion of black powder may be varied over a considerable range by suitably varying the proportions of the major components thereof, viz., potassium nitrate, sulfur and carbon. The rate of combustion may be further decreased by incorporating various amounts of suitable retarders, for example, potassium chloride, in the black powder. Thus, a long length of 1 may be formed

with a core 3 of progressively varying composition and hence combustion rate, consisting of, for example, straight black powder at one extremity and grading down to black powder admixed with considerable retardant at the other. The similar modification of cores containing, for example, alpha cellulose particles impregnated with a material capable of supplying oxygen should now be obvious. In such a case, the impregnated particles may be used exclusively at one extremity of the core while at the other extremity a considerable proportion of unimpregnated particles are to be found.

Similar methods may be used to control the combustion rate of long runs of devices such as are shown in Figures 2 and 3. With the device of Figure 2, for example, fibers 4 may be more strongly impregnated at one extremity of the long run than at the other. With respect to the device of Figure 3, the proportion of impregnated fibers 4 may be relatively high at one extremity of the long run and relatively low at the other.

Also, control of combustion rate may be achieved by providing devices of uniform cross sectional area as shown in the figures but provided with cores of progressively increasing cross sectional area on proceeding from one end of the run to the other. Or, the devices themselves may be made with a progressively increasing cross sectional area on passing from one extremity to the other. Additionally, a device having a uniform cross sectional area may be provided with a core having a cross sectional area varying periodically along the longitudinal dimension of the device, being of normal size for a short distance, tapering down to a mere train for a time, then expanding to normal size again, this periodic variation being continued throughout the longitudinal dimension of the device.

By the application of the above principles, a series of devices 1 may be provided, the devices in one series being, for example, 100 feet long and of such design as to insure combustion of a run of this length without reaching excessively high combustion rates. Other series may be provided, the members of each series being longer or shorter than the 100 feet mentioned above.

Also, it is possible to control combustion rate and avoid extremely high auto-accelerated combustion rates by purely mechanical means, involving the provision of suitable vents at spaced intervals along long runs of 1. This is illustrated in Figures 11 and 12, wherein 14 designates a section of a concrete, cement or similar structure containing a portion of a long run of device 1. In Figure 11, 1 is provided with a side member 15, reaching to the surface of the concrete, cement or similar structure. In Figure 12, 1 follows a sinuous path at the particular region illustrated, reaching the surface of the cement, concrete or similar structure at point 18. In both cases, vents are thus provided for the release of combustion pressure and, accordingly, auto-acceleration of the combustion rate to extremely high values is prevented. Obviously, these vents are distributed along long runs of 1 as necessary to accomplish the desired purpose. These vents may serve other useful purposes, for example, as outlets for electric wire or cable to be carried by the shaped passageway proper.

If desired, device 1 may be provided with a suitable fish wire to facilitate the pulling through

of electric wire or cable after the shaped passageway has been made as previously described. In Figure 5, a suitable fish wire 7 is shown within device 1. Fish wires are commonly made of iron or steel. In the present application, the fish wire is exposed to strong oxidizing conditions at elevated temperatures during the combustion process which may considerably weaken or even destroy an ordinary iron or steel wire. Accordingly, it is well here to coat such wires with a protective layer of a ceramic glaze or use wires more resistant to oxidizing conditions such as stainless steel or Nichrome (nickel-chromium alloy) wires.

By suitable modification, the devices of Figures 1 to 5 may be made to serve the dual purpose of draining excess water from plastic cement or concrete following which shaped passageways are formed therein as previously described.

As is well known, cement and plaster of Paris, to cite but two examples, are materials classified as hydraulic cements. That is, the set of these materials is due in large measure to chemical union of one or more components of the cement with water. The subsequent interlocking of the resulting hydrated crystals accounts in large measure for the strength exhibited after setting. Accordingly, hydraulic cements require a definite quantity of water in order to set properly and develop maximum strength. On the other hand, as a rule, mixtures of hydraulic cements and water usually require much more water than necessary for chemical reaction in order to produce a mix of sufficient plasticity to be handled easily. Once this plastic mass has been placed as desired, for example, in suitable forms, this water in excess of chemical requirements is no longer needed and, in fact, should be removed as completely as possible before proceeding further. By suitable modification, the devices of Figures 1 to 5 may be used to drain this excess water from the plastic cement or concrete following which shaped passageways may be produced as previously described.

Figure 6 is a general cross sectional view of a device suitable for accomplishing the two objects just outlined. In this figure, reference character 2 represents a relatively or completely water impervious layer or sheath which may be combustible or non-combustible, as desired, while 3 is a core capable of self-sustained combustion in the absence of air. Reference character 8 designates a drain member comprising a peripheral layer or sheath of absorptive material such as fibrous cellulose, rock wool, fiber glass and the like. The whole is surrounded by the freshly poured cement or concrete, as previously described. Excess water enters the peripheral sheath through capillary action and the like and drains from the exposed ends of the device, all as has been explained in detail in our co-pending application previously referred to.

Obviously, any of the devices of Figures 1 to 5 or any modification thereof may be provided with a drain member comprising a peripheral layer or sheath 8 of absorptive material for the accomplishment of the ends previously set forth.

If desired, the peripheral drain member 8, after discharging its primary function of removing excess water from the plastic cement or concrete, may then contribute to the subsequent formation of shaped passageways in the resulting structure. If the completely or relatively water impervious sheath 2 is combustible, part

or all of the drain member 8 will be consumed during the burn out operation, assuming, of course, that drain member 8 is made from combustible material, for example, cellulose fibers. The combustion of drain member 8 may be facilitated by incorporating therein a plurality of cores capable of self-sustained combustion in the absence of air. Such a device is shown in Figure 7. Here the peripheral drain member 8 carries a plurality of inserts 9, each consisting of a relatively or completely water impervious sheath 2A surrounding a core 3A capable of self-sustained combustion in the absence of air. The device of Figure 7, after exercising its drainage function, is allowed to dry out partially or completely following which it is ignited to form a shaped passageway in the structure.

Figure 8 shows another device capable of exercising the dual function previously described. In this figure, reference character 9 designates an absorptive, combustible member, such as a member made from cellulose fibers. This is placed in the plastic cement or concrete, as previously described, and facilitates the removal of excess water therefrom. After drainage is complete and member 9 has dried partially or completely, it is impregnated with a solution of an oxygen supplying compound, such as a solution of potassium, sodium or ammonium nitrate. Member 9 may be impregnated with such a solution by placing the free end or ends of 9 in said solution whereby the desired chemical is drawn into 9 by capillary action. Or, the solution may be pumped into 9 or may be added to 8 by other suitable means, for example, through the vents shown in Figures 11 and 12. After removal of most or all of the solvent, 9 may be ignited as usual to produce shaped passageways in the structure.

Devices with peripheral drain members 8 may be used, if occasion demands, to add water to cement or concrete to promote the curing thereof. For example, after excess water has been drained from the hydraulic cement and setting has taken place, peripheral drain members 8 may be saturated with water by methods explained in connection with the impregnation of the device of Figure 8 with a solution of an oxygen supplying compound, water being substituted for the solution. With respect to Figure 8, the solvent obviously is, in part at least, transferred to the hydraulic cement. Also, it is obvious that after shaped passageways have been formed, as previously described, these may be filled with water to promote curing. Many hydraulic cements set over a comparatively long period of time, some not reaching maximum strength for several weeks after being poured. During this period hydration is proceeding slowly and frequently water is required to accelerate and complete the process.

Many modifications, falling within the spirit and scope of the present invention, will occur to those skilled in the art to which it pertains. For example, while the devices shown in Figures 1 to 8 have circular cross sections, obviously, this is not a necessary requirement. Furthermore, while the devices shown herein, for example, in Figures 9 to 13, have uniform cross sections throughout their length, this, too, is not a necessary requirement. If desired, the devices of this invention may be of tapering cross section, as has been mentioned previously. Furthermore, it is within the purview of this invention to provide enlargements at spaced intervals along the

burn out device. These enlargements are also capable of self-sustained combustion on ignition and after combustion leave enlargements at spaced intervals within the structure which may serve, for example, as outlet boxes or receptacles for the installation of outlet boxes and for other similar purposes. Such a modification is shown in Figure 13, wherein device 1, at any desired point in its run, expands into the enlarged section 16. The core of this enlarged section is also capable of self-sustained combustion and is surrounded by a relatively or completely water impervious sheath. If device 1 is provided with a peripheral sheath of drain material as illustrated, for example, in Figures 6 and 7, then enlargement 16 is likewise provided with a peripheral sheath of drain material. It is not necessary that the enlargement 16 be an integral part of device 1, as shown in Figure 13. If desired, a separate enlarged section 16 of any size and shape may be placed contiguous to device 1 at any point of its run. This modification is shown in Figure 14. During combustion of 1, the immediately adjacent enlargement 16 also ignites and the combustion thereof produces a cavity of any desired size or shape at any desired point along the path of 1.

While this invention has been described in connection with comparatively long runs of the devices of Figures 1 to 8, this is obviously not a necessary limitation. Short length of these devices may be used to make corresponding cavities which may be used to receive bolts which are grouted in as usual and then used for the attachment of desired devices or structures to the cement or concrete. Or the cavities, after formation, may be filled with suitable material, for example, wooden pegs, for receiving nails, screws or the like in subsequent construction work. Another mode of application of a short run of the devices of this invention is shown in Figure 15. Here, a short length of the device 1 enters and leaves the construction member 14 at closely adjacent points. After combustion, a wire, cable, or the like may be passed into one orifice, through the short passageway and out the other. The resulting free ends of the wire, cable or the like provide means for attaching exterior members to the construction member 14.

Yet another mode of application of a short length of a modified form of device 1 is shown in Figure 16. In this embodiment, device 1 is provided with an integral, continuous helical rib 17 along at least a portion of the longitudinal dimension thereof. The pitch and size of the rib 17 are selected to conform to the pitch and depth of the thread on a bolt to be employed subsequently. After the burn out operation, it is obvious that a cavity is formed in 14 having an internal thread that will engage the thread of the selected bolt which may be screwed into the cavity as usual and used as a point of attachment for devices or structures exterior to 14. It is also apparent that the contour of the device may vary to form cavities for receiving various types of brackets and other devices.

This invention has been described largely in connection with hydraulic cements, but this is not a necessary limitation. Other materials of construction may be employed, in which case obvious modifications of the invention described may be desirable or necessary. For example, instead of being applied to cement or concrete, cast or molded plastics may be employed. In such cases, obviously peripheral drain members are unnecessary and undesirable. Also, relatively

or completely water impervious sheaths are unnecessary. When this invention is applied to plastics, novel effects may be achieved in some instances by incorporating certain materials into the peripheral layer of device 1, the nature of the material employed being governed by the plastic being used. Among such suitable materials may be mentioned trioxane or paraformaldehyde (urea-formaldehyde or phenol-formaldehyde resins), urea, melamine and catalytic agents such as peroxides, persulfates, acids and materials producing acidic fumes when heated. When employed in this modified form, shaped passageways can be formed in plastics which have a surface hardness appreciably above that exhibited by the plastic mass as a whole.

While in the preceding description device 1 was positioned and then surrounded with material in a plastic condition or was laid on a material in a plastic condition and then covered by additional plastic, this is not a necessary limitation. If desired, device 1 may be forced into a mass of material in plastic condition. For example, a length of device 1 may be laid upon the surface of a mass of plastic material and then forced into the body thereof by suitable forked bars. Or device 1 may be weighted, either continuously along its length or at spaced intervals so that when placed upon the surface of a plastic material, such as plastic hydraulic cement or a plastic body of earthy nature, it will sink beneath the surface thereof.

Be it remembered that, while the present invention has been described in connection with specific details thereof, these are illustrative only and in no way limit the spirit and scope thereof except insofar as such specific details are incorporated in the appended claims.

We claim:

1. A duct forming member of the character described comprising, in combination, a peripheral water absorptive sheath surrounding a relatively water impervious sheath, said relatively water impervious sheath in turn surrounding a core capable of self-sustained combustion. 40

2. A duct forming member of the character

described comprising, in combination, a peripheral water absorptive combustible sheath surrounding a relatively water impervious combustible sheath, said last named sheath surrounding a core capable of self-sustained combustion.

3. A duct forming member of the character described, comprising, in combination, a peripheral water absorptive sheath surrounding a relatively water impervious sheath, said relatively water impervious sheath in turn surrounding a core capable of self-sustained combustion, and a non-combustible element extending throughout the longitudinal dimension of said core.

4. A duct forming member of the character described comprising, in combination, a peripheral water absorptive sheath surrounding a relatively water impervious sheath, said relatively water impervious sheath in turn surrounding a core capable of self-sustained combustion, and a train capable of self-sustained combustion extending throughout the longitudinal dimension of said core, said train and core being so constituted that the rate of combustion of said train will be greater than the rate of combustion of said core.
